GEORGE W. DONNING, OF STAMFORD, AND DAVID ALEXANDER DONNING AND HARRY B. DONNING, OF STRATFORD, CONNECTICUT, ASSIGNEES, BY DIRECT AND MESNE ASSIGNMENTS, TO DONNING CARBURETER CORPORATION, OF ESOPUS, NEW YORK, A CORPORATION OF NEW YORK.

CARBURETER.

1,233,763.

Specification of Letters Patent. Patented July 17, 1917.

Application filed September 24, 1914. Serial No. 863,369.

To all whom it may concern:

Be it known that we, GEORGE W. DONNING, a citizen of the United States, residing at Stamford, in the county of Fairfield and State of Connecticut, DAVID ALEXANDER DONNING, and HARRY B. DONNING, citizens of the United States, residing at Stratford, in the county of Fairfield and State of Connecticut, have invented certain new and useful Improvements in Carbureters, of which the following is a specification, reference being had therein to the accompanying drawing.

This invention relates to carbureters.

15 A primary object of the invention is to construct a device which shall facilitate the making of high efficiency gas within the carbureter and effect an economy in the use of fuel; and one which is adapted to adjust 20 and control the temperature for hydrocarbons of different specific gravity to maintain the gas at a predetermined temperature irrespective of any sudden change in the weather (fair or stormy) or in the atmospheric temperature (hot or cold), wherefore no new 25 adjustments of the fuel are required; to reduce the loss of heat, due to cooling-fan and by radiation; to initially prime the inlet manifold with fuel; to initially heat the 30 carbureter and air-inlets, if desirable, independently of a motor cooling-system for facilitating the starting of a motor; and, if desirable, to cause the initial heater to be included in the cooling system.

35 A more specific object is to convert practically, if not all, of the globules of fuel into gas or vapor before being drawn into motor-cylinders and thereby greatly reduce, if not eliminate, the possibility of carbon depositing on the cylinder walls, etc.

40 A further object is to provide a heat-controlling structure, embodying certain of the underlying principles of our invention, which may be applied as an attachment to 45 any existing form of carbureter.

Among other though not essential features of our invention is the provision of a secondary air-valve and a hot-air conduit leading thereto, the valve being operated both automatically and manually to meet certain requirements, such as the adding of more air to the gas, the scavenging of the motor-cylinders, etc.

Other objects and advantages will in part be obvious from the annexed drawings while others will in part be pointed out in the following description.

The invention resides broadly in the features and construction, in the combination of elements, in the arrangement of parts, in the correlative aggroupment of a plurality of instrumentalities, all as will be exemplified in the construction hereafter set forth, and the scope of application of which will be indicated in the claims hereto appended.

In order that the invention may readily be comprehended, drawings illustrating some of the possible embodiments and utilizations of the same are hereto appended as a part of this disclosure. It is manifest, however, that other possible utilizations, embodiments and applications (employing the underlying principles of the invention) will fall within the spirit thereof and within the objects contemplated thereby.

In the drawings:

Figure 1 is a view in elevation, partly in section, of a carbureter constructed in accordance with one embodiment of our invention;

Fig. 2 is a fragmentary view, in rear elevation, of a needle-valve operating mechanism;

Fig. 3 is a fragmentary view, in vertical section, of the carbureter showing air and water-channels for effecting initial heating thereof; also an electric heater for warming the contents of said channels; also another form of gas-controlling valve within the mixing-orifice;

Fig. 4 is a detail view, in elevation (partly in section) of one of the controlling-valves;

Fig. 4^a is a fragmentary view in section, of a portion of the thermostatically-operated valve-device;

Fig. 5 is a view, similar to Fig. 1, illustrating a somewhat different embodiment of the invention and as applied to a carbureter of the Stromberg-type;

Fig. 6 is a detached view, in sectional elevation, of a float-valve;

Fig. 7 is a similar view of a thermostatic-device; and

Fig. 8 is a fragmentary view of an initial priming device.

Referring to the drawings, and to the em-

bodiment illustrated in Figs. 1 to 4 and 8, it will be seen that the reference-character 1 designates a motor-casing which, preferably and as usual, is provided with a water-cooling system (not shown).

5 Leading into the motor-casing is an inlet manifold 2 which communicates with a carbureter 3 preferably arranged in juxtaposition to the casing 1. The carbureter, in this 10 instance, is provided with water-circulating channels 4 which are utilized for effecting an initial heating of the structure, as presently hereinafter explained.

Communicating with the carbureter is a 15 temperature-controlling chamber 5.

Connecting, as by a conduit 6, with the 20 chamber 5 is a main heat-generating cylinder 7 through which extends an exhaust manifold 8 that, in turn, leads into the firing-chamber (not shown) of the motor.

25 Connecting with the carbureter-casing 3 or manifold 2 is a priming device which facilitates the making of gas and, hence, aids in the starting of the motor. A preferred form, 9, (Figs. 1 and 8) while herein shown, by way of example, as an attachment, to the inlet-manifold; yet it may be located within the manifold. The purpose of this priming-device is to supply a small quantity of fuel to each cylinder-inlet port just in advance of or while the motor is being cranked. In this instance, the primer 9 is provided with a single cup 10 which is common to primer outlet-pipes 11, and includes 35 an air-tight removable cap 12. The cup is filled with fuel which flows through the pipes 11 to small branches 13 extending into the manifold at each cylinder-port 14. Thus, the fuel commingles with air at the 40 instant a suction stroke of the motor is made. Instead of the cup 10, it is obvious that a fuel-supply-pipe (not shown), provided with a shut-off cock 10^a, could be used with similar results. It is within the contemplation of my invention that this initial 45 priming-device may be attached to the manifold of any existing motor, similar as herein revealed in connection with our structure.

Experience has shown that an initial or 50 primary heating of a carbureter is essential, especially when the temperature of the air is, say, 60°, or less; since it facilitates the making of gas and requires less fuel from the start, and a motor-car can always be 55 started quickly, even on a weak spark, irrespective of the spark-system employed, and whether high or low cylinder compression is employed. A saving of fuel, even of different grades, and ease of starting motor, 60 have been noted when the temperature of the air is as high as 90°. In addition, the initial heating prevents refrigeration at the constricted area of a carbureter—the place where it is essential that it should be warm 65 and not cold; and also prevents loss of heat

by radiation, since the heated air leading to the gas-making chamber is protected.

To this end, we have embodied an initial heating-device in the structure herein disclosed: In aeroplanes, automobiles, launches, etc. (where batteries are of small capacity) a carbureter with the initial heater similar to that shown will be employed: The enlarged channels 4 which surround a gas-making chamber 15 of the carbureter extend the entire length of the temperature-controlling chamber 5, which, at 16, leads into the conduit 6. The channel is provided with a capped filler-opening 17 and with an outlet-cock 18: To initially heat the entire device, a small quantity of hot water is poured through the opening 17 to fill the channels and, if desirable, the carbureter may then be primed and, thereafter, the motor cranked.

80 If desirable (though not essential) and when gasoline is used as fuel, the initial heating channel 4 may be connected to the water-cooling system of the motor by a pipe 19; which is provided with a shut-off cock 20, and, by a pipe 21, provided with a cock 22, to a regular pumping-device not herein shown but as is well understood in the art: When the cocks are opened, the water which has been warmed by passing around the 95 motor cylinder circulates through the initial-heating channel 4 and back to the pump through pipe 21. Of course, each time that the carbureter is initially heated, the cocks 20 and 22 in pipes 19 and 21, respectively, 100 are closed and the cock 18, in the bottom of the channel, is opened to draw off all cold water. Thereafter, the hot water which shall then have been introduced through the opening 17, circulates through the channel 4. 105 Now, after the motor has been running a while, the cocks 20 and 22 may be opened so that the water from the cylinder-walls of the motor will circulate into the channel 4.

110 In certain climates, where the temperature is fairly uniform and a good quality of gasoline is used, this method of continuous circulation of water would suffice to heat not only the long air inlet 5, but, also, the gas-chamber 15.

115 In automobiles, submarines, stationary motors, etc., equipped with batteries of sufficient capacity to cause an electric coil to become heated, we may utilize that form of device: To this end, we have, in Fig. 3, shown a channel 4 (as in the embodiment illustrated in Fig. 1), and this may be filled with air or any suitable heating liquid. Occupying part of the space therein, is an electric heating coil 24 with terminals 25 and 26 and wiring 27 leading to a battery 28. A switch 29 is disposed in the circuit for controlling the current from the battery to the coil. By this method, only a few minutes is required to heat up the contents in the channels of 120 125 130

the carburetor and, if the motor-cooling system is connected to the carburetor, cocks (not shown in this instance but corresponding to 20 and 22) would have to be closed to prevent circulation of the warm water to the cylinder as heretofore described at least until motor has been started.

Obviously, this initial heater may be adapted and used with any form of carburetor and produce improved results; and, although an advantage would be secured by employing the initial primer, also; still the combination is not an absolute necessity, since there are other forms of primers that might be employed.

To preclude climatic changes, the temperature of the different zones, or altitudes, from affecting the gas-temperature, we employ a main heat-generating and temperature-controlling device which coöperates effectively with the initial heating-device already described and influences the heat of it, so the latter in turn prevents loss of heat of the former by radiation. This structure—which permits changes to be made, manually, in the degrees of heat, and then maintaining the temperature at approximately any degree selected and which is done automatically—will enable a user to select any number of hydrocarbon liquids for fuel; or they can be mixed without impairing their effectiveness as an explosive fuel. For example, kerosene, with the proper degree of heated air (and even low-grade petroleum) may be used very effectively. Gasolene (plain or mixed with other grades of hydrocarbon liquids) can be used: Thus, in replenishing the supply a single receiving tank (not shown) is only necessary.

This heat-generating and controlling-device comprises the cylindrical heating chamber 7, surrounding the exhaust-pipe 8, is provided with small perforations 30 which permit air to be drawn into the chamber in a plurality of small streams simultaneously with each suction-stroke of the motor. At one side or end of the chamber 7, and preferably remote from the perforations 30, the temperature-controlling chamber 5 is connected. In this instance, this chamber has two inlets 6 and 32 and one outlet 31 which gives communication to the gas-mixing chamber 15; the inlet 32 opening from the atmosphere.

In the controlling-chamber 5 is suspended a thermostat 33. This thermostat, for convenience, is provided with a capped filling opening 34 (Fig. 7) and, at one end, with a stuffing-box 35 in which a piston rod 36 slides for controlling a valve 37 which, in this instance, and as shown in Fig. 4^a, is tubular, and it is mounted directly upon the piston rod and whereby it is given a reciprocating movement. The thermostat actuates the valve in one direction and a spring 38,

presently to be described, assists to return it. Thus, the inlet 6 and the outlet 32 are alternately covered, or partly so.

Within the thermostat 33 the piston-head 39 is provided with one or more holes 40 to permit the contents of cylinder to pass therethrough freely from one side of the piston-head to the other. The thermostat 33 is partly filled with a highly volatile liquid 41, the remaining space therein (42) being filled with air which may be slightly compressed. Where heat is applied to the cylinder, both the liquid and the air will expand. The air acts as a cushion and, thus, avoids the employment of a more costly form of thermostat-construction. In the meantime, sufficient pressure is developed to move the piston outwardly, that is, when the internal pressure of the cylinder exceeds the elastic controlling-device now about to be described. It is to be noted that the operative area of the surface on the left-side of the piston-head (Fig. 7) is considerably greater than that on the opposite side, since the latter is reduced to the extent of the diametral dimensions of the piston-rod 36. Therefore, there would necessarily be a preponderance of pressure on said left-side and this in practice has been found to be sufficient to overcome that on the opposite side. This permits the piston-head to move toward the right (Fig. 7) in the manner already described.

In this instance, the thermostat-piston rod 36 extends through the tubular slide-valve 37 and through the end of the chamber 5. Pivoted to a bracket 43 on the end of the chamber 5 is a lever 44 to which the piston rod 36 is connected. At the opposite end of the lever are a plurality of holes 44^a, and whereby adjustment may be effected between the action of the thermostat and the yielding member 38 which connects the lever 44 to a control-lever 45. This is mounted on any convenient stationary part and within reach of the operator. Coöperating with the control-lever 45 is a lever-locking device 46 which engages a segment 47 for the purpose of locking the lever 45 in any of a plurality of positions of adjustment. The segment 47 may be marked with certain designations, such as "A" for alcohol; "K" for kerosene; etc.; with degree-indicating marks; or with other appropriate indications.

Assuming that a mixture of kerosene and gasolene is to be used as the fuel, and that the lever 45 has been set properly; then the slide-valve 37 will be moved to cover the cold-air entrance 32 leaving the hot-air opening open so that, on each suction-stroke of the motor, hot-air will be drawn into the gas-making chamber from the main heat-generating chamber and heating the thermostat as it passes. As the temperature rises, the thermostatic pressure will overcome the

resistance of the yielding member 38 and cause the valve 37 to gradually close up the hot-air entrance and open the cold-air opening. If, for any reason, the temperature of the air varies, the thermostat will automatically act and regulate it by varying the position of the slide-valve relatively to the hot and cold openings. Should more heat be desired, for kerosene, say, the lever 45 10 would be thrown over to the left, thus setting up a greater resistance in the spring-member 38 and requiring a higher temperature to increase the thermostatic pressure sufficiently to overcome the stress of the 15 spring 38 when the temperature of the air exceeded that required or selected.

Obviously, this gas temperature controller may be used as an attachment to any known make of carbureter. As an additional feature for checking up the temperature of the 20 gas, a thermometer T may be placed in the inlet-manifold, as at 48.

In the present embodiment, we have included fuel-controlling and air adjusting-devices: As shown in Fig. 1, a bevel-seat valve 49, when seated, covers a fuel entrance, leading into the carbureter below the valve 49 and marked 50 in Fig. 2, and controlled by a needle-valve 51, which is operated by 25 a pinion 52, meshing with a sector 53 pivoted at 54 on the side of the carbureter. The valve 49 may, if desired, be provided with any well known form of spattering device. To impart, from a distance, movement to the sector 53 for the purpose of adjusting the quantity of fuel, a connecting-rod 55 is employed; and, in this instance, and as shown in Fig. 1, this rod is connected to a fuel-lever 56 which, in turn, is secured 30 to a tube (not shown) housed within a steering-post 58. Movement is imparted to the tube by a hand-lever 59, which co-operates with a rack-plate 60 to hold the lever in any selected position, as is well understood 35 in steering-post constructions.

In Fig. 3, we have shown a modified form of valve which, in this instance, is in the form of a tubular member 61 having its top formed with apertures 61^a, and provided 40 with openings 61^b, in its side, of varying size so that, as the valve 61 is lifted, as by the member 61^b, the quantity of gaseous mixture-flow is correspondingly varied. Carried by the valve 61 is a piece of mesh 62 45 for catching and spattering the fuel and for splitting up the air. A nozzle-entrance 61^c is shown in Fig. 3, and which is controlled by the tubular member 61.

Above and below these valves, in Figs. 50 1 and 3, are basins 63 formed for receiving the surplus fuel which is gradually evaporated as the warm air-current passes through the main air-inlet. A further commingling of the fuel and air occurs within the carbureter, as at 64 (Figs. 1 and 3).

A float-valve 65 for controlling the feed of a given quantity of fuel at a point between a main-supply tank (not shown) and the needle-valve is shown in Fig. 6. This may be incorporated in the carbureter, it-self, as shown in Fig. 5; or be placed at a point somewhat removed therefrom.

The fuel enters at the top 66 and forces a ball-valve 67 tightly against its seat 68. The flow of the fuel will then be directed 75 over the umbrella-plate 69 (suspended from the top of the float-chamber) and falls beyond the float-member 70. This float-member is positioned by the stem 71 connected to the ball which, as already explained, is controlled by the umbrella-plate 69. The stem operates in a guide 72 in the bottom of the valve-chamber. As the fuel rises in the chamber to a predetermined point, the float 70 is lifted and the 85 fuel supply is reduced or entirely cut off by the ball 67 as it nears or enters the upper valve-seat 73. A fuel-outlet 74 is provided; also a drain-cock 75. Within the carbureter or manifold is a throttle-valve 76 90 shown, in this instance, as operable by foot or hand: A throttle-lever 77 carries an extension 77^a which is intended for hand use. A rod 79 is also connected to lever 77 and, in this instance, is connected to a bell-crank-cam member 78, pivoted at 78^a to a suitable point of the motor or carbureter. At one end, the rod is encircled by a spring 80, one end thereof being secured to the rod 79, while the free end presses against the 100 underside of lever 77. Thus, when the lever is forced downwardly by hand, the spring 80 is compressed while the rod remains stationary. This permits the throttle-valve 76 to be opened. Upon releasing the lever, the 105 spring 80 will cause the valve to close.

To vary the size of the constricted section of the carbureter, the valve 49 (Fig. 1) or 110 61 (Fig. 3) will preferably be employed. The valve is held snugly in normal position by a spring 81 which surrounds a valve-stem 82 that passes through the bottom of the carbureter and is provided at its lower end with a nut 83. At each suction-stroke of the motor, the valve 49 is lifted slightly 115 from its seat and thereby uncovers the fuel-entrance to permit air to be drawn in and mixed with the fuel.

Under certain conditions—for example, in accelerating or throttling down the motor, 120 etc.—it is generally desirable to assist the motor in raising the valve 49 or to limit the height to which the valve should go. To this end, the bell-crank member 78 is provided with two cam-shaped fingers 84 and 85. 125 The latter is, preferably, forked to straddle and guide the valve-stem 82. To operate the bell-crank-cam-carrying member 78 from a distant point, a foot-treadle 86 is provided and connects with the member 78 130

through a rod 87. To restore the parts to normal position, a spring 88 is disposed in pressing engagement with the treadle 86. This foot-treadle bell-crank device is operated simultaneously with the throttle valve 76.

To one side of the gas-making chamber 15 is a secondary air-inlet 89 which is controlled by a valve 90 that may operate automatically, or manually, or not at all, at the will of the operator who may be stationed at a point somewhat remote from the valve. The valve 90 is provided with a plurality of small holes 91 (Fig. 4) in its face. The 10 valve may also be provided with apertures 91^a for permitting a small amount of air continuously to pass through the valve. A conduit 92 leads from the temperature-control-chamber 5 to the secondary air-inlet 89 and houses a portion of the stem 93 of the valve. The conduit is for providing air of the same temperature as that of the gas so as to avoid condensation. The valve-stem 93 extends through a bushing to a point outside of the conduit and supports a coil-spring 94, one end of which abuts against the bushing, while the opposite end carries an adjustable nut 95 for tensioning the spring. A second nut 96 is disposed on the 20 fine end of the stem. Both of these nuts provide working faces for a pivoted yoked finger 97. In this instance, a latch 98 is mounted on the steering-post 58 and, through a connecting-element 99 which 25 passes around rolls 100, is adapted to operate and control the finger 97. The latch 98 is slidably mounted on the steering-post, which is provided with a rack 101 for holding the latch 98 in any selected position.

When the locking member 98 is placed in a manner to give the yoke 97 ample freedom of movement, the valve 90 can then be actuated by suction into the gas-making chamber 15 a considerable distance provided the 30 nut 95 is adjusted remotely from the nut 96 and permit a large volume of air to enter. By shutting off the fuel, should the valve 49 not be working, the motor will draw in fresh air until it stops running, all of which will 35 aid in scavenging the motor-cylinders, or the fuel may be turned on again before the motor has actually stopped, thus permitting it to run as before scavenging. When the 40 yoke is so controlled as to permit only a slight movement of the valve 90, a limited amount of air will pass through holes 91 only. When the yoke is held tightly against the nut 96, there can be no movement of the 45 valve away from its seat; hence, no air can pass through the inlet-opening 89 except what can pass through the holes in the valve 50 whenever these are provided.

When the valve 90 is wide open, the flow of fuel may be shut off and the motor per-

mitted to operate while the automobile, say, 65 is coasting, and in this manner scavenging and cooling of the motor-cylinder is automatically accomplished. On the other hand, if the adjustment is made for the automatic action of the valve, as already described, the 70 valve will be effective only when the motor is going at high speed, when the gas mixture may be made "lean."

In Fig. 5, the structure is shown as applied to a water-jacketed carburetor of the 75 well-known Stromberg-type.

Leading into an inlet-manifold 102 is an initial primer 103 (similar to that already described and shown in detail in Fig. 8). A thermometer (not shown) is to be disposed at 104.

The initial heater, in this instance, extends into the temperature-controlling chamber 105 by a pipe-system 106 and is provided with the necessary cocks 107 and 108 to facilitate the emptying and filling of the pipe-system. In addition, this system may be included in the motor-cooling system or not, as desired.

Instead of a tubular slide-valve (like that shown in Fig. 1) for the hot-air intake 109 and the cold-air ports 110, we may employ two independent valves 111 and 112, respectively, for the intake 109 and the port 112. Both valves are operated in opposite directions by a thermostatic piston 113; that is to say, when the hot-air intake valve is closing, the cold-air-valve is opening, and vice versa. The valves are pivoted at the sides of the ports. Depending from the valves are actuating arms 114 and 115, respectively, which are connected to the piston as shown. To guide and balance the piston, a grooved roller 116 is provided at the bottom of the chamber, and the enlarged portion 117 is supported thereby.

In this construction, an elastic controlling-device, in the form of a spring 118, is mounted on the end of the piston rod. One end of the spring is secured to the piston rod, while the other is connected to a collar 119. This collar is adapted to slide on the piston rod when a yoke-lever 120 is adjusted, or during the action of the thermostat 121, which, in this instance, is the same as that already hereinabove described.

A hand-lever 122 is, by the rod 123, connected to the lever 120 and controls the action of the piston in much the same manner as the control-device described above in connection with the first embodiment.

In this particular embodiment, the invention is described as an attachment that is adaptable to any standard make of carburetor.

It is to be understood that either the initial primer or the initial heater, or both, may be omitted in certain embodiments if de-

sired. Moreover, the auxiliary air-ports may be supplied with the hot-air conduit, or not, according to requirements of use.

It has been found in practice that initially to heat the carbureter and intake manifold, it is only necessary to heat a very small quantity of water, and in this way create excellent gas-making conditions in the carbureter. This is obviously superior to the method which generally obtains, namely, drawing off the cold water from the motor-cooling system and then introducing several gallons of hot water to take its place: While this method will heat the cylinders, it does not initially heat the carbureter satisfactorily; and, besides, it involves labor and delay.

As many forms and types of carbureters are now on the market which are not water-jacketed, we find that a part or parts of our structure, as set forth hereinabove, can be attached thereto and excellent results thereby obtained.

It is to be understood that, in countries or zones where the atmosphere becomes exceedingly cold, the heat-generating chamber and inlet-manifold, one or both, may be protected by the continuation of the said water-jacket to protect them. In Fig. 1, the manifold is shown as provided with a channel 2^a which communicates with the water-circulating channel 4. For aeroplanes, this would be a desideratum.

With such constructions as herein described and illustrated, the need for self-starters is not as great; but, if employed as a convenience, it will be necessary to install less powerful devices than those which are now generally used.

40 Operation: To start and regulate a motor to which one of our carbureters is attached, the procedure would be about as follows:

After noting the kind of fuel being used, the adjusting lever 45, for controlling the gas temperature, according to scales, is set. The initial heater is then brought into operation and it, if necessary, produces a temperature equal to boiling water for any kind of fuel. This would, however, not be necessary in the event gasoline and other fuels of a similar specific gravity are used. Then, the carbureter is primed as usual. Or, if our initial primer is being embodied, the priming is accomplished through this instrumentality, and preferably so. In warm weather, this priming facilitates the starting of the motor, even though the initial heater is not then used.

60 The motor then having been cranked, as by giving the crank-shaft from a half to three-quarters of a turn, the carbureter is then able to gasify any of the fuels above specified, and it is immaterial if gasoline is followed by, say, kerosene, or vice versa. 65 The motor will run equally well with either

form of fuel. This is an important feature of the structure. The superior gas-making facilities, thus embodied, reduce the usually unpleasant odor of the exhaust gases.

From the foregoing, it will be perceived 70 that we have succeeded in devising a structure which is well adapted to achieve the several objects and ends in view. The structure is simple and compact in form and it is particularly well adapted for automobiles. 75 The parts of which it is formed are so constructed as to permit of its ready application to existing forms of carbureters.

As many changes can be made in the above-described constructions, and many 80 apparently widely different embodiments of the invention can be made without departing from the spirit thereof, it is intended that all matter contained in the foregoing description and shown in the accompanying 85 drawings shall be interpreted as illustrative and not in a limiting sense.

It is also to be understood that the language used in the claims is intended to cover not only the specific features of the invention but the generic features as well.

What we claim is:

1. A carbureter, including a casing, a chamber therein, a gas-manifold connected thereto, a channel in the casing and in the 95 manifold, a water-conduit leading from a water-supplying source outside the casing into said channel for introducing water thereinto, means for closing the water-conduit, and water-receiving and discharging 100 devices for the filling of water into, and withdrawal of the same from, the channel independently of the water in the aforementioned outside source.

2. A carbureter, including a casing, a 105 chamber therein, a gas-manifold connected thereto, a channel in the casing and in the manifold, a water-conduit leading from a water-supplying source outside the casing into said channel for introducing water 110 thereinto, means for closing the water-conduit, water-receiving and discharging devices for the filling of water into, and withdrawal of the same from, the channel independently of the water in the aforementioned outside source, and temperature-indicating means connected to the casing whereby the temperature of a fluid therein and in the manifold may be definitely ascertained.

3. In a carbureter, a casing, a gas-manifold connected thereto, a channel in the casing and extending into the manifold, an electric heating coil within the channel, a battery connecting with the coil for energizing it, and a switch for controlling the 125 current to the coil.

4. In a carbureter, a casing, an air-conduit communicating therewith, a channel equal in length to that of the casing and of the conduit, an electric heating element 130

within the portion of the channel surrounding the conduit, a battery, and a switch for controlling the current to the heating element.

5. A carbureter including a chamber provided with a plurality of ports, an air-conduit communicating with the chamber, a jacket encompassing the air-conduit and providing a channel therebetween for a temperature-changing fluid, and a heater communicating with the conduit and connected to the chamber-ports thereby.

6. A carbureter including a chamber having an air-inlet and a gas-outlet, an air-heater communicating with the chamber, a conduit connecting at one end with the air-inlet and having its opposite end provided with valve-controlled ports, one of which connects with the air-heater, and a thermos statically-operated tubular valve for controlling said ports.

7. A carbureter including a chamber having an air-inlet and a mixture-outlet, an air-heater, an air-conduit connected at one end with the air-inlet and having its opposite end provided with a plurality of valve-controlled ports, one of which communicates with the air-heater, means independent of the air-heater for heating the conduit, a temperature-regulating means within the air-conduit, and valve-mechanism connected to said regulating means and operative on said valves to control the ports.

8. A carbureter including a chamber having a gas-outlet and a plurality of air-inlets, an air-conduit connected to the chamber and feeding air into the chamber through all of the air-inlets and provided with a plurality of ports at its ends, means for controlling the air-inlets, operating-levers disposed remotely from the controlling-means, and connections between said means and levers.

9. A carbureter including a chamber having a gas-outlet and a plurality of air-inlets, an air-conduit connected to the chamber and feeding air into the chamber through all of the air-inlets and provided with a plurality of ports at its ends, means for controlling the air-inlets, operating-levers disposed remotely from the controlling-means, connections between said means and levers, and manually and automatically operated means for controlling the conduit-ports at predetermined degrees of temperature.

10. In a carbureter, a chamber provided with fuel and air inlets and a gas-outlet, a gas-manifold communicating with the chamber, an exhaust-conduit connected to the chamber, an air-heater communicating therewith, an air-conduit connecting the air-inlets with the heater, a channel adapted to be heated by said air-heater and surrounding the chamber, the conduit and the gas-manifold to prevent radiation of heated air passing from the heater to the chamber.

11. A carbureter including a casing, a main chamber therein, a temperature-controlling chamber communicating therewith for introducing a supply of heated air into the main chamber, a water-conduit leading 70 into the casing, a gas-manifold communicating with the main chamber, and a channel surrounding the main chamber, the controlling-chamber and the gas-manifold and communicating with said water-conduit, 75 whereby heated fluid from the conduit effects a heating of the contents passing from the controlling-chamber through the mixing chamber and through the manifold.

12. A carbureter including a chamber 80 provided with a plurality of ports, independent means for controlling said ports, an air-conduit connected to and communicating with said chamber and provided with a plurality of ports, an air-heater independent 85 of the chamber and connected to the air-conduit, means juxtaposed to the air-conduit and disposed independently of the air-heater for heating the conduit, independent connections between the ports in the chamber 90 and the air-conduit, and a valve for controlling the port of the chamber.

13. A carbureter including a casing, a chamber therein, a fuel-inlet leading thereto, primary and secondary air-inlets communicating with the chamber, a heating-chamber common to both inlets for supplying air at substantially the same temperature to both inlets, and means for controlling at least one of said inlets, comprising 100 a valve and mechanism for automatically controlling the same, including means for maintaining it open for a predetermined temperature.

14. A carbureter including a chamber provided with a secondary air-inlet, a fuel-inlet leading into the chamber, a primary air-inlet also leading into the chamber, an air-conduit leading into the primary inlet of the chamber and of relatively larger diameter than that of the secondary inlet, and a valve for controlling one of said inlets and having an orifice near its periphery adapted to be closed by the walls of the valve-seat when the valve is seated.

15. A carbureter including a chamber provided with a secondary air-inlet, a fuel-inlet leading into the chamber, a primary air-inlet also leading into the chamber, an air-conduit leading into the primary inlet of the chamber and of relatively larger diameter than that of the secondary inlet, a valve for controlling one of said inlets and having an orifice near its periphery adapted to be closed by the walls of the valve-seat when the valve is seated, and means for manually opening the valve.

16. A carbureter including a main chamber, a fuel-inlet leading thereto, an air-inlet leading into the chamber, an exhaust- 130

- heated chamber communicating with the main chamber and provided with an air-port, automatically-operated valve-mechanism for controlling the port, and expansion means connected with and operating said valve-mechanism for automatically opening and closing said port and including bodies of liquid and air housed within the exhaust-heated chamber.
10. 17. A carbureter including a main chamber, a fuel-inlet leading thereto, an air-inlet leading into the chamber, an exhaust-heated chamber communicating with the main chamber and provided with an air-port, automatically-operated valve-mechanism for controlling the port, expansion means connected with and operating said valve-mechanism for automatically opening and closing said port and including bodies of liquid and air housed within the exhaust-heated chamber, and manually-operated means for adjusting said valve-mechanism and cause it to become operative at predetermined temperatures.
15. 18. A carbureter including a carbureter-chamber, a second chamber for tempering air, a gas-inlet, a primary air-inlet, and a secondary air-inlet leading into the carbureter-chamber, both of said air-inlets leading from the air-tempering chamber, a valve for controlling the secondary inlet, and means for adjusting the valve to and retaining the same at any of its plurality of positions.
20. 19. A carbureter including a chamber provided with a combined fuel and air inlet and a secondary air inlet, a valve for controlling said secondary inlet, automatic means including a thermostatic device influenced by air passing into the air inlets for operating said valve, and manual means for actuating the valve at the will of the operator.
25. 20. A carbureter including a casing, a chamber therein, a fuel-inlet leading thereto, an air-heater, an air-conduit connecting the heater and the chamber, a thermostatic device operating to control air passing through the air-conduit, and a counter-acting device operative on the thermostatic device and adjustable into any of a plurality of positions.
30. 21. A carbureter including a casing, a chamber therein, a gas-manifold connected thereto, a channel in the casing and in the manifold, and a water-conduit leading from a water-supplying source outside the casing into said channel for introducing water thereto.
35. 22. A carbureter including a casing, a chamber therein, a gas-manifold connected thereto, a channel in the casing and in the manifold, a water-conduit leading from a water-supplying source outside the casing into said channel for introducing water thereto, and means for controlling the introduction of water into and its discharge from said chamber and manifold channels.
40. 23. A carbureter-structure including a mixing-chamber and a channel surrounding the mixing-chamber and provided with independent emptying and filling ports, a motor associated with the carbureter, a cooling-system therefor, connections between said cooling-system and the carbureter-channel, and means for controlling the flow of fluid through the connections.

In testimony whereof we affix our signatures in presence of two witnesses.

GEORGE W. DONNING.
DAVID ALEXANDER DONNING.
HARRY B. DONNING.
